CLAIM

The ornamental design for a baseball-themed beverage container, as shown and described.

DESCRIPTION

FIG. 1 is a front view of a baseball-themed beverage container of the present design, the rear view being identical thereto;

FIG. 2 is a right side view of the baseball-themed beverage container of the present design, the left side view being identical thereto;

FIG. 3 is a top front perspective view of the baseball-themed beverage container of the present design;

FIG. 4 is a bottom rear perspective view of the baseball-themed beverage container of the present design;

FIG. 5 is a top view of the baseball-themed beverage container of the present design;

FIG. 6 is a bottom view of the baseball-themed beverage container of the present design;

FIG. 7 is a bottom perspective view of the baseball-themed beverage container of the present design, wherein the container is tilted more horizontally than in FIG. 4; and,

FIG. 8 is a top perspective view of the baseball-themed beverage container of the present design, wherein the container is tilted more horizontally than in FIGS. 4 and 7.

The broken lines show portions of the baseball-themed beverage container that form no part of the claimed design.

1 Claim, 8 Drawing Sheets
